United States Patent Office

Des. 191,774
Patented Nov. 14, 1961

191,774

GRAVE MARKER

Waneta N. Oberther, 202 Parkhurst St., Elkland, Pa.

Filed Aug. 12, 1960, Ser. No. 61,717

Term of patent 14 years

(Cl. D79—2)

FIG. 1.

FIG. 2.

FIG. 3.

FIG. 4.

The rear of the grave marker is substantially plain. The dominant features of my design reside in the portions shown in full lines.

I claim:

The ornamental design for a grave marker, as shown and described.
